CLAIM

The ornamental design for an architectural panel with a zig zag pattern, as shown and described.

DESCRIPTION

FIG. 1 is a top perspective view of an architectural panel with a zig zag pattern when arranged with other architectural panels of corresponding design in a ceiling structure;

FIG. 2 is an isolated, top perspective view of the architectural panel shown in FIG. 1;

FIG. 3 is a bottom perspective view of the architectural panel shown in FIG. 2;

FIG. 4 is a top, plan view of the architectural panel shown in FIG. 2;

FIG. 5 is a side view of the architectural panel shown in FIG. 1; and,

FIG. 6 is an end view of the architectural panel shown in FIG. 1.

The broken line showing of environment in the drawing of FIG. 1 is included for the purpose of illustrating only and forms no part of the claimed design.
